(57) **CLAIM**

The ornamental design for a recessed light fixture, as shown and described.

DESCRIPTION

FIG. 1 is a perspective view of a recessed light fixture showing our new design.

FIG. 2 is a top plan view of the recessed light fixture of FIG. 1.

FIG. 3 is a left elevation view of the recessed light fixture of FIG. 1.

FIG. 4 is a front elevation view of the recessed light fixture of FIG. 1.

FIG. 5 is a right elevation view of the recessed light fixture of FIG. 1.

FIG. 6 is a bottom plan view of the recessed light fixture of FIG. 1; and,

FIG. 7 is a rear elevation view of the recessed light fixture of FIG. 1.

The recessed lighting fixture is shown broken away to indicate that the area between the break lines forms no part of the claimed design.
